UNITED STATES PATENT OFFICE.

WILLIAM P. DAY, OF CLEVELAND, OHIO.

RAIL-SUPPORTING STRUCTURE.

1,420,974.

Specification of Letters Patent. Patented June 27, 1922.

Application filed July 30, 1921. Serial No. 488,652.

To all whom it may concern:

Be it known that I, WILLIAM P. DAY, a citizen of the United States, residing at Cleveland, in the county of Cuyahoga and 5 State of Ohio, have invented certain new and useful Improvements in Rail-Supporting Structures, of which the following is a specification.

This invention relates to structures for 10 supporting rails, and particularly to that type of structure wherein the rail is supported upon a concrete bed and supported along its entire length.

It is a well known fact that while it is 15 advisable that rails be given a firm support upon a continuous bed, yet the difficulty with such a continuous bed is that the rail does not have a sufficient elastic or cushioning support and as a consequence "chattering" 20 is liable to occur. Furthermore, the rail will not stand the stress and the pounding to which it is subjected as well as it would if a cushion or elastic support is provided for the rail.

25 The general object of my invention is to provide a structure which supports the rail practically along its entire length as distinguished from supporting it at relatively wide intervals, but in which a relatively 30 yielding support is provided for the rail, and more specifically in which this support consists of a block or blocks of wood extending beneath the rail and longitudinally thereof, and in which the rail is further

35 yieldably supported by a metallic plate disposed between the rails and the supporting blocks, the upper surface of which plate is corrugated or formed with alternate crests and relatively shallow valleys so that the 40 "wave" in the rail caused by the passage of wheels thereover may be accommodated.

A further object is to provide a construction of this character wherein the wood supporting blocks are entirely housed or 45 encased and protected from the weather so that they will remain effective for a relatively long period and will not need frequent renewals, and further to so form the structure that these wooden blocks may 50 be removed and replaced whenever desired without the necessity of in any way tearing up or disassembling the track structure itself.

Another object in this connection is to 55 provide a rail supporting structure of the character described which may be embedded

in concrete and which will yet yieldingly support the rails, and in which the rail supports are tied together so as to form what is known in the art as a twin tie 60 structure.

Other objects will appear in the course of the following description.

My invention is illustrated in the accompanying drawings, wherein:—

65 Figure 1 is a top plan view of a rail supporting structure formed in accordance with my invention;

Figure 2 is a side elevation of the metallic skeleton of the structure;

70 Figure 3 is a cross sectional view of the completed rail structure embedded in concrete;

Figure 4 is an enlarged cross sectional fragmentary view through the rail supporting structure;

75 Figure 5 is a longitudinal sectional view through the plate 20;

Figure 6 is a rear elevation of one of the fastening members 16.

80 Referring to these drawings, it will be seen that I have illustrated a skeletal supporting structure wherein two parallel rail supports are provided connected by transverse tie bars. Each rail supporting structure comprises a longitudinally extending base plate 10 having a width greater than the width of the base of the rail and in actual practice having a width of some 15" 85 more or less.

90 Riveted, bolted or otherwise attached to this plate 10 are the two parallel angle irons 11 and 12, 12 being the outermost angle irons, these angle irons being of any desired or practical length and being riveted by 95 rivets 13 or bolted to the plate 10, the outer edges of the angle irons coming flush with the outer edges of the plate 10. The vertical flanges of the angle irons 11 and 12 are perforated at intervals for the passage of transverse bolts 14. Disposed within the trough formed by the angle irons 11 and 12 and the bottom plate 10 is a wooden block or 100 wooden blocks.

I have illustrated the more or less elastic 105 filler 15 as being formed of two sections, each of these sections being formed of a wooden block, the grain of which runs longitudinally. The space between the confronting faces of the vertical flanges of angle 110 irons 11 and 12 is greater than the width of the base of the rail A, and disposed at in-

tervals are the rail fasteners 16 which have vertically extending shanks and which are formed with somewhat vertically elongated openings 17 through which the bolts 14 pass. 5 The upper ends of these fasteners have heads 18 which project beyond the shank and are beveled upon their under faces so as to engage over the base of the rail A, as illustrated in Figure 4. The openings 17, 10 as remarked, are somewhat elliptical vertically and therefore the major axis of these openings has a length of about $\frac{1}{8}$ " greater than the minor axis of these openings so as to permit these rail engaging members 15 to shift vertically about $\frac{1}{8}$ ". Preferably tar or an equivalent material is melted and poured into the space between the wooden blocks 15 and the inner faces of the vertical flanges of the angle irons 11 and 12, this 20 tar seeping between the lower faces of the wooden blocks and the top surface of plates 10 so that the wooden blocks are thoroughly embedded in the thin layer of tar which will act to protect these blocks from the effects 25 of moisture. The upper faces of the blocks 15 may also be covered with a coating of tar and resting upon the upper faces of the blocks or upon this coating of tar is a rail supporting plate 20 having a width equal to 30 the distance between the vertical flanges of the angle irons 11 and 12 and being cut out at intervals, as at 21, to accommodate the fastening devices 16 which fit these openings 21 snugly. While I do not wish to be limited 35 to this, I preferably form the upper surface of this plate 20 with transversely extending corrugations, as illustrated in Figure 5, so that the upper surface of the plate is formed with alternate raised and de- 40 pressed portions or alternate peaks and valleys. Preferably, though I do not wish to be limited to this, the valleys 22 will be about $\frac{1}{8}$ " deep and there will be a distance of about 6" between crests. The object of 45 so forming this plate 20 is to accommodate the wave given to the rail by the passage of a car wheel thereover.

It will be seen that by tightening up the nuts on the ends of bolts 14 that the fastening devices will clamp the base of the rail A firmly but that these fastening devices will not prevent the depression of the rail under weight or the rise of the rail as the weight is relieved, due to the expansion of the 55 wood. The twin rail supporting structures which I have just described are connected at intervals by means of cross bars 23 of angle iron or channel iron, preferably channel iron, with the flanges extending downward so that they shall be embedded in the concrete of the roadway and will act to prevent longitudinal movement of the rail 60 structure.

At the joints between the plates 10, I provide relatively short, transversely extending

I-beam sections 24, the plates 10 meeting at the central axis of the I-beam 24 but the flanges 11 and 12 meeting to one side of the central axis, as at 25, so that the angle irons 11 and 12 break joints with the joint of the 70 plates 10. One of the plates 10 and its corresponding angle irons 11 and 12 are riveted at the factory to one flange of the I-beam section 24, and when the track structure is assembled the projecting end of the plate 75 10 of the next adjacent section is inserted between the horizontal flanges of the angle irons 11 and 12 and the projecting flange or head of the I-beam 24 and bolted thereto, as by the bolt 26.

It will be seen that the sections of the track structure are preferably assembled and riveted at the factory and that then these sections are assembled in the field by connecting them together by the bolts 26. 85 The metallic track supporting structure described is disposed upon a concrete bed 27 and concrete 28 is filled in between the vertical flanges of the outer angle iron 12 and the end of the concrete base 27 and between the 90 confronting vertical flanges of the angle irons 11, as at 29. This concrete 29, as illustrated in Figure 3, has its upper surface extended downward to a space midway between the rails so as to form a drainage 95 channel between the rails, and embedded in the concrete 18 is a drain pipe 30 and there are drainage openings 31 formed in the concrete 29 which extend to this branch pipe, thus securing a thorough drainage for the 100 track structure, carrying off all water and thereby preventing the deteriorating action 105 of moisture upon the wooden blocks 15.

It is to be particularly noted that the wooden blocks 15 are entirely housed from 110 moisture. They are protected at the bottom by the plate 10 and the layer of tar, they are protected at the sides by the vertical flanges and the angle irons 11 and 12 and by the layers of tar, and they are protected at 115 the top by the plate 20 and by a layer of tar which may be disposed upon the top faces of the blocks immediately below this plate 20. Thus only minimum moisture can ever get to the wooden blocks, and therefore these wooden blocks which are creosoted or impregnated with other preserving compositions will last for a relatively long time. By the track structure which I have 120 described I secure a resilient or yielding 125 foundation for the track which is built very largely of structural steel and in which only a minimum of wood is used but wherein the rail is supported along its entire length instead of at intervals, as is the case where ties are used. The particular form of the upper surface of the plate 20 is of great moment, as this particular form permits a wave caused by an advancing wheel to travel longitudinally along the rail. Obviously the 130

distance between the crests of the corrugations will depend upon the length of this wave, the crests of the corrugations being disposed at the nodal points of the wave.

5 As a train passes over the rails A, these rails will not only vibrate longitudinally but they will be depressed and thus the plate 20 will be depressed against the wood blocks 15, which will yield to this pressure, and 10 after the train has passed, the elasticity of the wood will cause the plate 20 and the rails to move back to their initial positions.

While I have referred to certain dimensions of the several parts, it is obvious that 15 I do not wish to be limited to these nor to many of the details of construction, as these details might be modified in many ways without departing from the spirit of the invention as defined in the appended claims.

20 I claim:—

1. A rail supporting structure of the character described formed to provide a channel extending longitudinally of and beneath the rail for the entire length of the rail, an elastic filler disposed in said channel, a plate disposed within the channel and upon which the rail rests and extending the entire length of the channel and rail, said plate having alternate crests and valleys upon its upper surface, said corrugations extending at right angles to the length of the rail and the rail being compressible into the valleys under tractive effect, and means for holding the rail against said plate.

35 2. A rail supporting structure of the character described formed to provide a channel extending longitudinally of and beneath the rail, an elastic filler disposed in said channel, a plate disposed within said channel and 40 directly supporting the rail, and rail engaging means disposed within said channel, said means having slight vertical movement.

3. A rail supporting structure formed to provide a channel extending longitudinally 45 of the rail and having vertical side walls, a filler of elastic material disposed within said channel and between said side walls, a rail supporting plate resting upon said filler, fastening devices adapted to engage over the 50 base of a rail and extending down into said filler and through the plate, and bolts passing through the side walls of the channel and through said fastening devices, the apertures in said fastening devices for said 55 bolts being vertically elongated.

4. A rail supporting structure of the character described formed to provide a channel extending longitudinally of the rail to be supported and beneath the same, said channel being closed at its bottom and sides, wooden blocks disposed in said channel, a rail supporting plate resting upon the wooden blocks, rail engaging devices extending downward through said wooden blocks and 65 through the plate, and transverse bolts pass-

ing through the side walls of the channel and through said fastening devices and the wooden blocks, the fastening devices having vertically elongated apertures for the passage of said bolts.

5. A rail supporting structure of the character described comprising a base plate, angle irons attached to the base plate and having vertical flanges defining a channel between said vertical flanges, a filler of elastic material disposed in said channel, a plate resting upon said filler, bolts extending through the vertical flanges of the angle irons at intervals, and rail engaging fastening devices through which said bolts pass extending through said plate and having slight vertical movement with relation to the bolts.

6. A rail supporting structure comprising a base plate extending longitudinally of the rail to be supported, angle irons mounted upon said base plate and having vertical flanges defining a longitudinally extending channel wider than the base of a rail, wooden blocks disposed within said channel, tar coating the faces of the wooden blocks, a metallic plate resting upon the wooden blocks and adapted to support the rail, rail engaging members adapted to engage the base of a rail and extending downward through said plate and into said blocks and having vertically elongated apertures, and bolts passing through the vertical flanges of the angle irons, through said fastening devices, and the wooden blocks.

7. A track supporting structure of the character described formed to provide two parallel channels adapted to extend longitudinally of the track rails, wooden blocks mounted in each of said channels and extending longitudinally beneath the rails, plates disposed in each channel and extending longitudinally of the rails, rail engaging devices having shanks extending vertically downward through said plates and into the blocks, transverse bolts connecting the vertical walls of each channel and extending through the fastening devices, the fastening devices having slight vertical movement with relation to said bolts, and transversely extending tie bars connecting said channels at intervals.

8. A rail supporting structure formed of longitudinally extending sections, each section being formed of a longitudinally extending base plate, angle irons attached to said base plate and having vertically extending flanges defining a channel between them, cushioning blocks disposed in said channel, a metal plate disposed in the channel, rail engaging members extending downward through the plate and into said wooden blocks and having vertically elongated apertures, bolts passing through the vertical flanges of the angle irons and extending through the apertures of the rail engaging

devices, the base plates of adjacent sections being abutted against each other, a cross bar disposed immediately beneath the joint between the base plates, the angle irons of adjacent sections having their joints staggered with relation to the joints between the base plates, the base plate and said angle irons being attached to the cross bar.

9. In a rail supporting structure, an elongated rail supporting plate adapted to extend longitudinally of the rail and having its upper surface formed with alternate rel-

atively shallow crests and relatively shallow valleys, the crests and valleys extending at right angles to the longitudinal axis of the plate and the apices of the crests being relatively acute, the rail normally resting upon said crests and the crests being spaced apart approximately as far as the width of the rail base to permit the rail to be depressible into the valleys under tractive effect.

In testimony whereof I affix my signature.

WILLIAM P. DAY.
